TUBE CLEANER

Wilfred Whealy, Hobart, Ind., assignor to
Standard Oil Company, Chicago, Ill., a corpora-
tion of Indiana

Application July 12, 1934, Serial No. 734,817

3 Claims. (Cl. 15—104.13)

This invention relates to improvements in tube cleaners and more particularly to tube cleaners of the rotary cutter type.

Prior to my invention various types of tube cleaners employing driven cutters have been used for cleaning the bore of the metal tubing used in tubes of pipe stills, boiler tubes and similar apparatus thereby to remove accumulations of carbon and other solid deposits from the inner 5 tube walls. It is important in the cleaning of tubes and pipes in such apparatus as employed in the refining of petroleum that the cleaning operation be conducted in as short a time as possible thereby to provide a minimum interruption or 10 shut-down of the processes for which the apparatus is employed.

Of the various types of tube cleaners available for use the cutters are in most instances located upon an axis or axes parallel to the axis of the 20 tube to be cleaned. This arrangement is not objectionable where the deposit of carbon or solid material is relatively thin but in such cases as encountered in the majority of tube cleaning operations in the petroleum industry the carbon or 25 solid deposit within the tubes is relatively thick and sometimes all but completely closes the tube or pipe. Under such a condition the conventional type of tube cleaner employing cutters upon axes parallel to the tube are wholly inadequate to perform the tube cleaning operation 30 within a reasonable time due principally to the fact that the central portion of the cutter rotates at such a low circular velocity that the cutting away of the deposit at the central portion of the tube is necessarily slow and hence the advance 35 of the cutter along the tube is retarded even though the rim speed of the cutter adjacent to the inner walls of the tube is sufficiently high to provide for a reasonable cutting speed. Upon many 40 occasions, under the conditions described, the retarding of the advance movement of the cutter along the tube axis results in serious scoring and abuse to the tube walls.

It is therefore an object of my invention to 45 provide an improved tube cleaner which may be advanced through a tube to be cleaned, wherein the tube is completely, or nearly, closed by carbon or other similar deposits upon the inner wall thereof, at a speed approximating that at which 50 the cutter may be advanced in a tube which has a relatively thin deposit upon the inner wall.

A further object is to provide a tube cleaner of the character described wherein maximum peripheral speed of the cutting edges of the rotary 55 cutters thereof is maintained throughout the en-

tire diameter of the tube thereby to provide equal cutting action throughout the entire cross-section of the accumulated deposit to be removed.

Other objects, the advantages, and uses of the invention will be apparent after reading the following description and claims and after consideration of the drawing forming a part of this specification wherein,

Fig. 1 is a side elevation of a tube cleaner constructed in accordance with the invention; 10

Fig. 2 is a sectional view of the cutting head of the cleaner as it appears during the cleaning operation;

Fig. 3 is a side elevation of another form of the tube cleaner; and 15

Fig. 4 is a view similar to Fig. 2 of another form of the cutting head.

With reference to Figs. 1 and 2, I have selected for illustration therein a tube cleaner comprising in general a pair of hollow hemispherical cutters 20 2 and 3 mounted upon the respective outer ends of opposed shafts 6 which are inclined slightly, forward to a plane perpendicular to the longitudinal axis of the cleaner and therefore to the axis of the tube 4 to be cleaned. Each hollow 25 hemispherical cutter is mounted on its respective shaft 6 for rotation about an axis perpendicular to the plane of the hemisphere. The cutters 2 and 3 may be driven through the medium of a transmission comprising a pair of bevel gears 30 5, one upon the inner end of each of the cutter shafts 6 which gears mesh with a bevel drive gear 7 carried upon the outer end of the drive shaft 8 of an air motor 9 of conventional structure.

The transmission thus described may be housed 35 within a sealed hollow spherical housing 11 located within the opposed hemispherical cutters as illustrated in Fig. 2. The interior of the housing may be filled with a suitable lubricant. I prefer to make the housing 11 of two parts with 40 a suitable gasket 12 therebetween in order to facilitate the introduction and assembly of the cutters and drive gears therein. The innermost section 13 of the housing 11 may be formed integral- 45 ly with the tubular bearing and support 14 for the drive shaft 8 and connected, as by a bushing 15, with the housing of the air motor 9 as shown. If desired, an apron 16 to surround and protect the rearward portion of the hemispherical cutters 2 and 3 may be located concentric with the 50 tubular portion 14 of the housing and secured thereto by a lock nut 16a. The apron 16 prevents the stream of air passing through the open- 55 ings 19 of the air motor 9 (hereinafter described) from forcing coke and other solid material into

the space between the forward edges of the cutters 2 and 3. The apron 16 also functions to deflect the current of air from the openings 19 of the air motor 9 toward the inner wall of the tube 4 being cleaned and around the cutters 2 and 3 thereby blowing the loose coke toward the forward end of the tube. The cutters 2 and 3 may have conventional cutting blades as indicated at 17, extending radially from the axis of the cutter shafts 6 to the periphery of the cutters. In operation the entire cutter and motor assembly may be introduced into the tube 4 to be cleaned as indicated in Fig. 1 and manually advanced along the axis of the tube. The arrangement of the cutters 2 and 3, as will be apparent, are such as to provide maximum peripheral speed of the cutting blades at the central portion of the tube, and therefore with a coke or carbon deposit, such as indicated at 18, upon the tube wall, the action of the cutters will have maximum cutting efficiency, not only at the portions of the tube section adjacent to the inner walls thereof, but also at the approximate center of the tube. Thus, the cutting away of the deposit throughout the entire tube section is uniform and the advance of the tube cleaner accompanied by the manual rotation of the entire cleaner assembly about its longitudinal axis will result in the cutting away and removal of the deposit in a minimum of time per linear unit of tube. It is contemplated, as in the case of the conventional type of tube cleaner, that the exhaust air from the air motor 9 discharged through the exhaust openings 19 of the motor will add in the scavenging of the particles of the removed deposit through that section of the tube forwardly of the cutter thereby to maintain the motor free of contact with the hard material of the deposit.

In Fig. 3 I have illustrated another form of the cleaner assembly wherein the cutting head is constructed precisely in the same manner as indicated in Fig. 2 but is connected with the air motor 9 through a long flexible drive shaft 21 which may be enclosed in a conventional flexible torque tube 21a. The advantage of this arrangement is that the motor 9 need not enter the tube during the cleaning operation and therefore the possibility of damage to the motor by the introduction of hard carbonaceous material into the moving parts of the motor or bearings is precluded. As above described the entire cleaning unit may be manually rotated.

In Fig. 4 I have illustrated another form of the cutter head wherein a single hemispherical cutter 22 is employed and mounted upon a shaft 23 extending at an angle of substantially 33° from the longitudinal axis of the tube cleaner and of the tube. The driving connection between the cutter shaft 23 and the shaft 8 of the air motor 9 may comprise a universal drive 24 located within a closed housing 25 filled with a suitable lubricant. The cutter of Fig. 4 possesses the advantages of that described in connection with the cutter head of Fig. 2 and in addition the advantage of utmost simplicity of construction and low cost. This modification has the additional advantage in that the maximum peripheral speed of the cutting edges of the cutter is not only at the central portion of the tube as in the case of the cutting edge first described but is also at the inner wall of the tube. The tube cleaning

unit thus described is manually rotated within the tube during the cleaning operation to remove all of the carbon or solid deposit therein as above mentioned.

Although I have described my invention in terms of certain specific embodiments thereof, numerous modifications will be apparent in the light of my specification to those skilled in the art and I do not desire to limit my invention except to the scope of the appended claims.

I claim:

1. In a tube cleaning device for coring out tubes which have become coked or otherwise choked up, a cutter assembly adapted to be introduced into a tube and moved longitudinally thereof, comprising a hollow spherical housing adapted to retain a lubricant, said housing having radially disposed journals formed in the wall thereof, one of said journals adapted to receive a drive shaft longitudinally disposed within said tube, a second of said journals receiving a second shaft disposed at an angle to said drive shaft greater than a right angle, a hollow hemispherical member embracing said spherical housing and mounted on the outer end of said second named shaft for rotation about an axis perpendicular to the plane of said hemisphere, cutting blades formed on the outer periphery of said hemispherical member and extending radially from the axis of rotation thereof, and means connecting said second named shaft with said drive shaft operating within said spherical housing in contact with said lubricant.

2. In a tube cleaner, a cutter assembly to be introduced in a pipe for coring out the same, comprising a hollow spherical gear housing provided with a first journal for receiving a drive shaft transverse to the longitudinal axis of a tube to be cored out and having a beveled gear on the inner end thereof within said housing, said housing being further provided with two opposed journals each having a shaft therein and each provided with a beveled gear within said housing and positioned for driving relation with said first named beveled gear on said drive shaft, and a pair of hollow hemispherical members having their hollow portions facing each other and embracing said housing and being supported on the outer ends of said last two named shafts for rotation about an axis perpendicular to the plane of the hemisphere, said hollow hemispherical members each being further provided with cutting edges thereon diverging radially from the axis of rotation, each of said last two named shafts being positioned at an angle relative to said driving shaft which is slightly greater than a right angle whereby the planes defined by the opposed faces of said hemispherical cutters converge at a point slightly beyond the forward portion of said assembly.

3. The structure as defined in claim 2 wherein the said housing is provided with an extension of said journal carrying said drive shaft, said extension being wedge shaped to fit within the diverging faces of the rear portion of said cutters, and being further characterized by the provision of a saucer shaped apron thereon partially embracing the rear portion of said cutter assembly, whereby to assist in preventing the entrance of loose material within said cutter assembly.

WILFRED WHEALY.
